(57) **CLAIM**

We claim an ornamental design for a bottle, as shown and described.

DESCRIPTION

FIG. 1 is a front/left/top perspective view of a bottle according to an exemplary embodiment;

FIG. 2 is a front elevational view thereof, for which the rear elevational view would be identical;

FIG. 3 is a right side elevational view thereof, for which the left side elevational view would be identical;

FIG. 4 is a top plan view thereof; and,

FIG. 5 is a bottom plan view thereof.

The evenly-dashed broken lines in the drawings illustrate the portions of the bottle that form no part of the claim. The dot-dash broken lines in the drawings define the bounds of the claim and form no part thereof.
